UNITED STATES PATENT OFFICE.

DE LOS E. HIBNER AND FREDERICK W. LINAKER, OF DUBOIS, PENNSYLVANIA,
ASSIGNORS TO THE VULCAN SOOT CLEANER CO., OF PITTSBURG, PA., OF
DUBOIS, PENNSYLVANIA, A CORPORATION OF NEW JERSEY.

"OILER-FLUE-CLEANER SYSTEM.

1,144,543.

Specification of Letters Patent. Patented June 29, 1915.

Application filed June 16, 1914. Serial No. 845,411.

To all whom it may concern:

Be it known that we, (1) DE LOS E. HIBNER and (2) FREDERICK W. LINAKER, (1) a citizen of the United States and (2) a subject of the King of England, residing at Dubois, in the county of Clearfield and State of Pennsylvania, have invented certain new and useful Improvements in Boiler-Flue-Cleaner Systems, of which the following is a specification.

This invention relates to boiler flue cleaner systems, of the type employing a fluid-distributing pipe provided with discharge nozzles, so disposed with relation to the longitudinal axial center of said pipe, and to a bank of boiler tubes as to discharge steam or other cleaning fluid in oblique streams through the spaces between the boiler tubes.

The present invention is designed as an improvement upon the type of flue cleaners disclosed in United States Letters Patent No. 1,041,079 granted to De Los E. Hibner under date of Oct. 15, 1912, and in United States Letters Patent No. 1,041,141, granted to James Moore, Oct. 15, 1912.

In Letters Patent No. 1,041,079 above referred to, a plurality of fluid-distributing pipes is employed, each having a plurality of discharge nozzles interposed and arranged to discharge fluid at an oblique line with respect to the axis of the distributing pipe and flue. The other patent above referred to, No. 1,041,141 embodies the features just described, in combination with means for rotating the distributing pipes to vary the angular positions of the discharge nozzles with relation to the boiler flues, and thereby change the direction of oblique travel of the stream of cleaning fluid, to effect a cleaning of the entire surface of the tubes.

The primary object of this improvement is to accomplish the results aimed at by both of the patented inventions above-identified, by greatly simplified means, and to materially reduce the cost of installation of boiler flue-cleaning apparatus operating on the principle hereinbefore outlined.

Another object, and an important one of this improvement, is to provide intersecting cones of blast without the streams of fluid forming said cones crossing each other when issuing from the directing nozzles.

Briefly stated, the invention employs a rotatable fluid-distributing pipe having suitable feed and supply pipe connections, provided with a plurality of discharge-nozzles located at different radial angles with respect to the axis of the distributing pipe, whereby a single distributing-pipe will be adapted to direct streams of cleaning fluid along different lines of obliquity, thus adapting one pipe to direct streams of cleaning fluid to a tube surface area which has heretofore been cleaned only by the employment of two distributing tubes. By this construction and arrangement, the nozzles will lie in different planes radiating from the longitudinal axis of the fluid-distributing pipe, the nozzles being angularly-displaced around the pipe, preferably providing a spiral arrangement, the degree of angularity however, being variable as conditions may require.

The invention will be fully described hereinafter in connection with the accompanying drawings which form a part of this specification, and its distinguishing features over the prior art will be set forth and defined in the appended claims.

In the drawings: Figure 1 is a view in elevation, with the boiler setting broken away showing a flue cleaner system embodying the invention, it being understood that in practice, the branch-pipes and feed pipe are outside the boiler setting as shown in Fig. 2. Fig. 2 is a horizontal sectional view of a boiler setting showing a top plan of the cleaner system installed in position with relation to the tubes of a boiler of the well-known B. and W. type. Fig. 3 is a transverse vertical sectional view of a boiler and its setting as shown in Fig. 1, and partly-broken away to show the arrangement and disposition of the nozzles of the distributing pipes with respect to the passage-ways between adjacent rows of tubes. Fig. 4 is a detail plan view partly broken away, of one of the fluid-distributing pipes. Fig. 5 is a section on the line V—V of Fig. 4. Fig. 6 is a detail plan view similar to Fig. 4 of a modified construction of liquid-distributing pipe. Fig. 7 is a section on the line VII—VII of Fig. 6, and, Fig. 8 is a detail view partly in section showing one end of the rotatable fluid-distributing pipe located in the soot chamber of the boiler setting.

When the improvement is applied to a boiler of the type shown, the construction and arrangement of the nozzles of the distributing pipes enable us to arrange the distributing pipes at spaced points directly overlying the battery of tubes, thus obviating any difficulty in disposing the distributing pipes among the tubes of the battery or boiler.

- 10 The reference numeral 10 designates a feed line connected at one end to a steam supply 11 having a drain valve 12. The feed pipe is provided with a shut-off valve 14 located adjacent the supply pipe 11, and 15 at or near its opposite end is preferably provided a drain valve 15. Branch pipes 16 extend upward from the feed line at desired intervals and each is provided with a shut-off valve 17 preferably located at a 20 point close to the feed line. Elbow pipes 18 connect the upper ends of the branch pipes 16 with the distributing pipes 19 arranged above the tubes 20 of the boiler. These distributing pipes are extended through one 25 side wall of the boiler setting and may be journaled at their inner ends in the opposite side wall, but we prefer to support the pipes intermediate their inner ends and the installation wall by means of bracket clamps as 30 17' which are clamped on the water tubes of the boiler being provided with openings for the distributing pipes so as to constitute journals for the latter. A branch pipe 21 connected with the feed line 10 at a suitable 35 point extends down to the soot chamber of the boiler setting, and is connected with a transversely-disposed distributing pipe 22, rotatable on its longitudinal axis and preferably journaled at the inner end in the opposite wall. The pipe 22 has a plurality of 40 openings or nozzles disposed intermediately throughout the length of the pipe to discharge the cleaning fluid which may be directed to all parts of the soot chamber to 45 create a strong blast of steam which will carry out through the stack the soot which has been dislodged from the tubes, together with the accumulation that has lodged in said soot or combustion chamber. The nozzles 25 of the pipes 19 are so disposed that 50 the cleaning agent is projected between the lines of the different rows of tubes as best shown in Fig. 3, so that steam issuing from the nozzles will be projected through the 55 space 26 in such a manner that as the distributing pipe is rotated, the arc traversed increases so that the projected steam strikes the flues more or less as the bottom flues of the battery are reached, the steam being 60 projected in the space cleaning the flues on opposite sides and its later contact with the flues direct serving to dislodge all soot which may have dropped thereon from the flues above. In order to keep the soot cleaned 65 from the sides of the boiler setting, each

distributing pipe is provided adjacent the ends with an opening as 29, projecting downwardly at direct right angles to the axis of the pipe, and cleaning the inner side of the boiler setting, as well as the flues which are 70 located adjacent to such sides of the boiler setting.

The numerals 30 and 32 designate the usual headers, and 31 and 33, the baffle-plates of a B. and W. boiler, and the disposition of the pipes 19 is such that the steam from the nozzles 25 is directed in oblique streams between all of the tubes or flues of the battery.

As shown in Figs. 4 and 5, the nozzles 25 are disposed at different radial angles to each other, preferably at angles of between twenty and thirty degrees, but the precise degree of angularity may be varied.

In Figs. 6 and 7, we have shown a modification in which the nozzles 25^a of the distributing pipe 19 are disposed at points diametrically opposite each other. This arrangement is within the scope of the invention, as well as all such further modifications as will insure the issuing of the steam in streams of varying obliquity, so that the number of distributing pipes to clean the entire battery of flues is reduced to the minimum, only four of such pipes being necessary in the embodiment shown in Figs. 3 and 4.

It will thus be seen that any pair of the nozzles, such as the pair 25 shown in Fig. 4 or the pair 25^a shown in Fig. 6 are arranged in such manner as to produce two cones of blast when the pipe 19 is revolved but that the streams of fluid producing these cones do not interfere so that there is not caused an appreciable change of direction of these streams such as would occur did the streams intersect.

What we claim as new is:—

1. In a flue-cleaner system, a fluid-distributing pipe equipped with a plurality of sections revolvably connected together, certain of said sections having discharge nozzles and the nozzles being disposed in different planes radiating from the longitudinal axis of the fluid-distributing pipe, to discharge fluid in a plurality of streams from a single pipe on oblique lines with respect to the axis of the distributing pipe.

2. In a flue-cleaner system, a rotatable fluid-distributing pipe having a plurality of sections 110 revolvably connected together, certain of said sections having discharge nozzles and the nozzles being obliquely-disposed with respect to the axis of the pipe, each of said nozzles being angularly displaced about said pipe with respect to the adjacent nozzles.

3. In a flue-cleaner system, feed and supply pipes, in combination with a rotatable distributing pipe provided with a plurality 130

- of sections revolvably connected together, certain of said sections having discharge nozzles and the nozzles being each disposed radially of the axial center of said pipe and 5 being angularly displaced about said pipe with respect to the next adjacent nozzle, whereby a single distributing pipe is adapted to discharge a plurality of jets or streams of fluid on lines of different angularity.
- 10 4. In a flue-cleaner system, feed and supply pipes, in combination with a fluid distributing pipe provided with a plurality of sections threaded together, certain of said sections being provided with obliquely disposed discharge nozzles, and means for rotating said distributing pipe to discharge fluid in a plurality of streams successively through said nozzles in paths of varying obliquity.
- 15 5. In a tube cleaner system for boilers having rows of inclined tubes disposed to provide oblique spaces between the rows of tubes, the combination with the tubes, of a revolvably-mounted fluid distributing pipe 20 arranged at right angles to said tubes, a feed pipe therefor, a supply pipe to which the feed pipe is connected, a plurality of nozzles interposed in the pipe and each having its outlet disposed obliquely to the axis 25 of the pipe, said nozzles being spirally-arranged about said pipe and disposed to project fluid along generating lines of intersecting cones, the nozzles lying in different planes radial to the axis of the pipe where- 30 by the cone-generating jets pass free from each other.
- 35 6. In a tube cleaner system for boilers having rows of inclined tubes disposed to provide oblique spaces between the rows of tubes, the combination with the tubes, of a revolvably-mounted fluid distributing pipe 40 arranged at right angles to said tubes, a supply pipe, a feed pipe connecting the supply and distributing pipe, a plurality of nozzles interposed in the pipe and each having its outlet disposed to project fluid at an oblique angle to the axis of the pipe into spaces between the rows of tubes, said nozzles being spirally-arranged about said pipe and 45 disposed to project fluid along generating lines of intersecting cones, the nozzles lying in different planes radial to the axis of the pipe whereby the cone-generating jets of fluid pass free from each other, means for 50 rotating said pipe, and a rotatable distributing pipe arranged in the soot chamber of the boiler and connected to said feed pipe.
- 55 7. In a tube cleaner system for boilers having rows of inclined tubes disposed to provide oblique spaces between the rows of tubes, the combination with the tubes, of a revolvably-mounted fluid-distributing pipe arranged at right angles to said tubes and provided with a plurality of nozzles throughout, the nozzles being alternately inclined longitudinally of the pipe whereby to project fluid along the generating lines of a plurality of pairs of cones, the discharge ends of the nozzles being fixed at all times with respect to the inlet ends thereof and the nozzles 60 being disposed in different planes radial to the axis of the pipe whereby the jets of fluid of cone-shape issuing from the nozzles pass free from each other on lines oblique to the axis of the distributing pipe.
- 65 8. In a flue cleaner system, a flue, a rotatably-mounted steam distributing pipe arranged at an angle to said flue, a supply pipe, a feed pipe connecting the distributing pipe to the supply pipe, and a plurality of 70 nozzles in the distributing pipe having lateral outlets disposed to project the steam obliquely to the direction of draft of the products of combustion passing around the flue, said nozzles being spirally arranged about said pipe.
- 75 9. In a flue cleaner system, a rotatable fluid distributing pipe provided with a pair of nozzles having their axes in planes radial to the axis of the pipe, said nozzles being 80 arranged when rotated to develop intersecting cones of projected fluid with the projected streams of fluid free from each other with any position during the revolution of the pipe.
- 85 10. In a flue cleaner system, a rotatable fluid distributing pipe provided with a pair of nozzles arranged to project fluid along generating lines of intersecting cones, said nozzles lying in different planes radial to 90 the axis of the pipe whereby the generating jets pass free from each other.
- 95 11. In a flue cleaner system, a rotatable fluid distributing pipe provided with a plurality of sets of nozzles alternately inclined longitudinally of said pipe whereby to project fluid along the generating lines of a plurality of pairs of intersecting cones, each nozzle of one set being disposed angularly about said pipe with respect to the adjacent 105 nozzle of the other set whereby the generating jets of intersecting cones generated by adjacent nozzles pass free from each other.
12. In a flue cleaner system, a rotatable fluid distributing pipe provided with a plurality of sets of nozzles alternately inclined longitudinally of the pipe whereby to project fluid along the generating lines of a plurality of sets of cones, the cones of one set intersecting the cones of the other set 110 and the nozzles being disposed in different planes radial to the axis of the pipe whereby the jets of intersecting cones pass free from each other.
- 115 13. In a flue cleaner system, a rotatable fluid distributing pipe provided with a plurality of sets of nozzles alternately inclined longitudinally of said pipe whereby to project fluid along the generating lines of a plurality of pairs of intersecting cones, each nozzle of one set being disposed angularly 120 about the adjacent nozzle of the other set whereby the generating jets of intersecting cones generated by adjacent nozzles pass free from each other.
- 125 14. In a flue cleaner system, a rotatable fluid distributing pipe provided with a plurality of sets of nozzles alternately inclined longitudinally of said pipe whereby to project fluid along the generating lines of a plurality of pairs of intersecting cones, each nozzle of one set being disposed angularly about the adjacent nozzle of the other set whereby the generating jets of intersecting cones generated by adjacent nozzles pass free from each other.

ject fluid along the generating lines of a plurality of pairs of intersecting cones, the discharge ends of the nozzles being fixed at all times with respect to the inlet ends of 5 the nozzles and each nozzle of one set being disposed angularly about said pipe with respect to the adjacent nozzle of the other set, whereby the generating jets of steam describing intersecting cones generated by adjacent nozzles pass free from each other on 10 lines oblique to the axis of the distributing pipe.

14. In a flue cleaner system, a revolvable fluid distributing pipe provided with a plurality of sets of nozzles alternately inclined 15 longitudinally of the pipe whereby to project fluid along the generating lines of a plurality of sets of cones, the discharge ends of the nozzles being fixed at all times with respect to the inlet ends of the nozzles and the 20 nozzles so disposed that the cones of one set intersect the cones of the other set and the nozzles being disposed in different planes radial to the axis of the pipe whereby the 25 jets of steam describing intersecting cones

pass free from each other on lines oblique to the axis of the distributing pipe.

15. In a flue cleaner, a flue, and a revolvable fluid distributing pipe arranged at right angles to the flue and provided with a series 30 of fixed spirally arranged nozzles, the fixed longitudinal axis of the discharge end of each nozzle being at a predetermined and permanently-established acute angle to the longitudinal axis of the distributing pipe, 35 whereby to project fluid along the generating lines of a plurality of sets of cones, the nozzles being so disposed in different planes radial to the axis of the distributing pipe whereby the jets of steam describing intersecting cones pass free from each other on lines oblique to the axis of the distributing pipes.

In testimony whereof we affix our signatures in presence of two witnesses.
